US00D588119S

(12) **United States Design Patent**
Griffin

(10) **Patent No.:** **US D588,119 S**
(45) **Date of Patent:** **** Mar. 10, 2009**

(54) **KEYBOARD FOR A HANDHELD MOBILE COMMUNICATION DEVICE**

(75) Inventor: **Jason T. Griffin**, Kitchener (CA)

(73) Assignee: **Research in Motion Limited**, Waterloo, Ontario (CA)

(**) Term: **14 Years**

(21) Appl. No.: **29/246,548**

(22) Filed: **Apr. 21, 2006**

Related U.S. Application Data

(63) Continuation of application No. 10/785,790, filed on Feb. 24, 2004, now Pat. No. 7,083,342.

(51) **LOC (9) Cl.** **14-03**

(52) **U.S. Cl.** **D14/247; D14/455**

(58) **Field of Classification Search** ..... D14/137-138, D14/147-148, 156, 218, 247-248, 341-347, D14/496, 390, 399, 138 R, 138 AA, 455-456; D16/208; D21/329, 331, 333, 517; 348/14.01-14.02; 361/814; 379/433.01-433.13; 455/556.1-556.2, 455/575.1, 575.3, 575.4, 566, 90.3; D13/164, D13/168; 439/165; 343/702

(57) **CLAIM**

I claim the ornamental design for a keyboard for a handheld mobile communication device, as shown and described.

DESCRIPTION

The FIGURE is a front elevational view of a keyboard for a handheld mobile communication device.
